[57] CLAIM

The ornamental design for a valve, as shown and described.

DESCRIPTION

FIG. 1 is a perspective view taken from the top, front and left side of a valve showing our new design;
FIG. 2 is a front elevational view thereof, the rear being a mirror image of the front;
FIG. 3 is a top plan view thereof;
FIG. 4 is a bottom plan view thereof;
FIG. 5 is a left side elevational view thereof; and,
FIG. 6 is a right side elevational view thereof.

FIG - 6FIG - 5FIG - 3FIG - 4
